UNITED STATES PATENT OFFICE.

CHARLES HENREY WILSON, OF PADUCAH, KENTUCKY, ASSIGNOR OF ONE-HALF TO JAMES OWEN, OF SAME PLACE.

LOCOMOTIVE.

SPECIFICATION forming part of Letters Patent No. 359,947, dated March 22, 1887.

Application filed October 28, 1884. Serial No. 146,690. (No model.)

To all whom it may concern:

Be it known that I, CHARLES HENREY WILSON, a citizen of the United States, residing at Paducah, in the county of McCracken and State of Kentucky, have invented a new and useful Improvement in Locomotives, of which the following is a specification, reference being had to the accompanying drawings.

My invention relates to an improvement in locomotives; and it consists in the peculiar construction and combination of devices, that will be more fully set forth hereinafter, and particularly pointed out in the claims.

In the accompanying drawings, Figure 1 is partly a side elevation and partly a vertical central longitudinal sectional view of a locomotive with my improved devices attached thereto. Fig. 2 is a vertical sectional view of the same, taken on the line xx of Fig. 1. Fig. 3 is a detailed view.

This improvement relates more particularly to locomotive-engines; but it may be applied to steam-boiler or other furnaces.

The object of the invention is to provide improved devices for arresting the sparks and to do away with the annoyance of smoke, soot, dust, &c., and to increase the draft and decrease the consumption of fuel.

Referring by letter to the drawings, A designates the boiler of the locomotive, which is provided with the fire-box or furnace B, the grate C, the ash-pit D, flues E, smoke-box F, and stack G, in the usual manner. In the smoke-box, directly facing the head of the boiler, is a hood, H, which forms an elbow or rearwardly-extending horizontal portion of a spark-funnel, I, which is secured vertically in the smoke-box and extends downwardly below the lower side thereof for a suitable distance. The bottom of the spark-funnel is formed by the pivoted balanced valve K, to the protruding ends of the shaft of which are secured levers L, that are weighted at their lower ends, so as to keep the valve K normally in a horizontal position, closing the lower end of the spark-funnel. A cord or rod, M, is secured to the upper end of one of the levers L, and extends therefrom to the cab of the locomotive in easy reach of the engineer.

N represents pipes that extend from the ash-pit and enter the hood H, and have their ends

turned downwardly therein, and O represents pipes that are connected to the steam-chests of the engines and conduct the exhaust-steam therefrom into the hood, as shown, the arrows 55 which are not feathered indicating the currents of exhaust-steam in the drawings.

P represents a sleeve, which is placed on the end of the hood and is adapted to slide back and forth thereon. Lugs R project from the 60 outside of the hood, and similar lugs, S, project from the outer side of the sleeve, and to the lugs S are secured rods T, that pass through eyes formed in the lugs R. The sleeve is provided with a funnel-shaped mouth, P', corresponding in size to nearly the diameter of the boiler. The sleeve is moved back and forth on the hood by means of a lever, U, fulcrumed in the front side of the smoke-box, and a rod, V, connecting one end of the lever with the sleeve, 70 and an actuating-rod, W, that extends from the opposite end of the lever to the cab within easy reach of the engineer, who can thus cause the sleeve to close or enlarge the opening to the chimney, and thus regulate the draft. 75

The exhaust-steam from the pipes O forces the smoke, gases, &c., which enter the hood from the boiler-flues and the sleeve through the pipes N into the ash-pit beneath the grate. The smoke, gases, &c., mingled with the exhaust-steam are consumed by the fire in the fire-box, creating a strong draft and an intense heat, and enable slack coal or screenings or other cheap fuel to be used to make steam. 80

Among the advantages gained by my improved devices is that the two or three upper rows of boiler-flues will not become choked with soot, as is the case with the locomotives in common use, and, owing to the greatly-increased draft, steam can be made in plenty with 90 very little labor. When going downgrade, and on other occasions when steam is not needed to be supplied to the engines, the sleeve can be moved in against the head of the boiler, and thereby almost entirely cut off the draft, 95 and thus effect a great economy in fuel. The sparks, cinders, and heavier products of combustion will fall into the smoke-funnel I, and be extinguished by the water resulting from condensation of a portion of the exhaust-steam. 100 When a sufficient quantity of extinguished sparks and cinders have accumulated in the

spark-funnel, the engineer can, by drawing upon the cord or rod M, tilt the valve bottom K and drop the contents of the spark-funnel onto the ground.

5. I claim—

1. The combination of the hood H, located in the smoke-box, the exhaust-pipes O, extending therein, and the pipes N, leading from the hood to the ash-pit, whereby the smoke and gases mingled with exhaust-steam will be returned to the furnace and the draft therein increased, substantially as described.

2. The combination of the hood H, located in the smoke-box and having the movable sleeve P, for regulating the draft, the exhaust-pipes O, extending into the hood, and the pipes N, leading from the hood to the ash-pit, for the purposes described, substantially as set forth.

3. The combination of the spark funnel or receiver I, located in the smoke-box and hav-

ing the hood H and the tilting bottom or valve, with the exhaust-pipes O, extending into the hood, and the pipes N, leading from the hood to the ash-pit, substantially as described.

4. The combination of the spark funnel or receiver I, located in the smoke-box and having a bottom or valve adapted to discharge its contents, and the hood H, with the exhaust-pipes O, extending into the hood, the pipes N, leading from the hood to the ash-pit, the sleeve P, sliding on the hood and having the funnel-shaped mouth, and means for moving the sleeve to regulate the draft, substantially as described.

In testimony that I claim the foregoing as my own I have hereto affixed my signature in presence of two witnesses.

CHARLES HENREY WILSON.
